ASSIGNORS TO CONSOLIDATED CAR-HEATING COMPANY, OF ALBANY, NEW YORK, A
CORPORATION OF WEST VIRGINIA.

AUTOMATIC DEFLECTOR FOR ELECTRIC CAR-HEATERS.

1,269,589.

Specification of Letters Patent. Patented June 18, 1918.

Application filed February 1, 1915. Serial No. 5,534.

To all whom it may concern:

Be it known that we, THOMAS FARMER, Jr., and ERNEST D. JANSEN, both citizens of the United States, residing, respectively, at 5 New York city, county and State of New York, and Albany, county of Albany and State of New York, have invented certain new and useful Improvements in Automatic Deflectors for Electric Car-Heaters, the following being a full, clear, and exact disclosure of the one form of our invention which we at present deem preferable.

For a detailed description of the present form of our invention, reference may be had 15 to the following specification and to the accompanying drawing forming a part thereof, in which—

Figure 1 is a plan and

Figs. 2 and 3 are sections of an electric car 20 heater and deflector therefor arranged according to our invention.

In an electric heater employed for railway cars having cross seats, it is desirable to direct the heat coming from the heater either 25 to one side or the other of the seat as the latter is shifted to face one end or the other of the car.

For that purpose we provide a tilting deflector on the upper side of the heater which 30 may be set to divert the heat toward the front or the rear of the heater casing, according to the position of the particular car-seat to which it pertains. In particular we mount this deflector on the heater—not on 35 the car-seat—and provide a spring connection from the deflector to the seat mechanism whereby the turning of the seat will also tilt the deflector.

Referring to the drawing, B, B represent 40 two castings placed as the support under the opposite ends of the seat C. These castings and the seat C thereon are arranged to be tilted as shown in Fig. 2 when the seat faces one end of the car, and to be tilted 45 versely, as shown in Fig. 3, when it faces the opposite end. Since the seat itself with its reversing mechanism forms no part of my invention, the showing thereof in the drawing may be taken as representing any suitable car-seat and reversing devices therefor. H is the electric heater-casing, it being understood that the heating coils therein are to be of any desired kind. This heater

casing is provided with brackets h, h that rest on the angle-bars A¹ and A² of the base 55 which supports the seat. Above the heater H is the deflector D in the form of a rectangular plate pivoted on its longer axis in the uprights K at either end of the heater casing. Being thus pivoted the deflector-plate can be turned into the position, relative to the heater, shown in Fig. 2, or it can be turned into the oppositely inclined position shown in Fig. 3. In either case the heated air rising from the heater will be deflected to one side thereof. In Fig. 2 the hot air will be deflected to the rear of seat C which faces to the left, and in Fig. 3 it will still be deflected to the rear of the seat which now faces to the right, the slant of the deflector being in the opposite direction.

To operate the deflector D, it is only necessary to provide a yielding wire connection between it and a shifting point on the seat. For example, we connect one end of a helical 75 spring S to a short lever-arm R on the axis of the deflector and connect the opposite end of the spring to a wire W which leads to the arched extension T on the adjacent casting B. Thus, as the seat and casting B are 80 shifted from the position of Fig. 2 to the reversed position shown in Fig. 3, the wire W will draw on lever-arm R of the deflector and tilt it correspondingly. In other words the shiftable deflector is mechanically 85 a part of the heater and not a part of the seat mechanism, the wire and spring serving merely as an elastic link to connect the two for operating purposes. By this means the heater and its deflector can be installed separately from the seat without being involved in the construction and operation of the seat-shifting mechanism, whatever such mechanism may be. It will be understood that the deflector may be of any appropriate form, 95 either flat, as shown, or curved, or of other suitable conformation, and that the operating connection may be of any different form or attached to any available point of the seat that shifts when the seat is shifted, 100 though preferably it will need to be yielding or elastic and of a link form.

What we claim as new and desire to secure by Letters Patent is:

1. The combination with a heater casing 105 adapted to inclose a heater, of a reversible

- deflector member supported thereby, and a yieldable actuating device for imparting reversing movements to said deflector member.
2. The combination of a heater casing 5 adapted to inclose a heater and having uprights thereon, a deflector member pivotally supported at its ends in said uprights and provided at one end with an operating arm, a spring member attached at one end to said 10 arm, and an operating link connected to the other end of said spring and adapted to be attached to a shiftable element, whereby reversing movements may be imparted to said deflector.
- 15 3. The combination with a heater casing provided with uprights, of a deflector member pivotally supported between said uprights, an operating arm attached to said deflector member, and a yieldable actuating 20 device connected with said arm for imparting reversing movements to said deflector and for maintaining the same in its extreme positions.
4. The combination with a heater casing 25 adapted to inclose a heater, of a flat deflec-

tor plate pivotally mounted at its ends on the exterior of the casing and reversible to deflect the heat therefrom to either side thereof, and means connected to the deflector, whereby reversible movement may be 30 imparted to said deflector.

5. The combination with a heater casing adapted to inclose a heater, of a deflector plate pivotally mounted at its ends exteriorly of and on top of the casing to rotate 35 about its axis and to be reversible for directing heat over the casing and to either side thereof, and means connected to the deflector, whereby reversible movement may be 40 imparted to the latter.

In witness whereof we have hereunto set our hands, before subscribing witnesses.
